CAR DOOR CONSTRUCTION

Joseph Lukaszewski, Hammond, Ind.

Application June 9, 1939, Serial No. 278,193

1 Claim. (Cl. 20—32)

This invention relates to improvements in car door construction and has for one of its principal objects the provision of means for operably associating a lift type sectional closure in a car door opening.

The present method of forming a closure between a conventional car door and the material loaded within the car consists of securing boards or the like to the wooden door posts. The boards are usually fastened with nails or spikes which results in damage to the door post. Moreover, closure boards cannot be nailed or readily secured to the new type cars in which metal door posts are used.

The present invention provides means whereby a closure member, consisting of either a sectional door or individual boards, may be secured in place between either metal or wooden door posts.

Another object of advantage and importance of the improved construction resides in the provision of means whereby closure members may be removably positioned in the doorway of a car having either metal or wooden door posts.

Still another object of importance resides in the economical production and installation of the door post facing member of this invention.

Additional objects of advantage and importance will become apparent as the following detailed description progresses, reference being had to the accompanying drawing, wherein

Fig. 1 is an elevational view of a car door opening, parts thereof being broken away, which embodies the invention.

Fig. 2 is a vertical section taken on line 2—2 of Fig. 1.

Fig. 3 is a section taken on line 3—3 of Fig. 1.

Fig. 4 is a slightly modified form of a door post facing member.

Fig. 5 is a section taken on line 5—5 of Fig. 4.

Fig. 6 is a section taken on line 6—6 of Fig. 4.

Fig. 7 is a section of a slightly modified form of a sectional closure member.

As shown in the drawing:

The reference numeral 10 indicates generally a car door opening. The frame thereof may be of either wood or metal construction.

Positioned on each side of the door opening 10 is a door post 12. The door posts 12 may be formed of wood or metal or any other suitable material.

Positioned on each door post 12 is a door post facing member 14. The members 14 may be bolted, riveted or otherwise suitably secured to the door posts 12.

Formed in each facing member 14 and extend-

ing longitudinally thereof, is a groove 16. When the facing members 14 or 14a are operably positioned in the doorway, the grooves 16 are on opposite sides of the door opening and form a track or guideway for moving a door therein.

In the preferred embodiment of the invention, the groove 16 near the upper end of each facing member is curved, as is best shown in Fig. 2. Each curve has a radius great enough to allow a flexible door to be moved therein from a vertical to a horizontal position and back without binding.

Joined to each facing member near the upper end thereof, and forming a continuation of the groove 16, is a channel shaped member 18. It is to be noted that this construction provides a track, in which a door may be operated, extending from the door opening upwardly and inwardly across the car.

Positioned in the grooves 16 and operable throughout the continuation of said grooves as formed by the channel members 18, is a sectional closure member 20. The closure member 20 is preferably formed of a plurality of boards maintained in loose association by means of flexible metal strips 22, as is best shown in Figs. 1 and 3.

The slots 24 in the flexible strips 22, allow the securing means 26 and through them the boards of the closure 20 limited independent movement. The independent movement allows the boards of the closure member 20 to separate sufficiently to negotiate the curve in moving from the vertical to the horizontal position.

Secured to the closure member 20 and extending to a point near the upper end of a door post 12 is a cable 27. A counterweight 28 is attached to the free end of the cable. The counterweight and cable assembly are attached to facilitate operation of the closure member 20.

A modified form of a closure member 20a is shown in Fig. 7. This closure member 20a consists of a plurality of joined metal strips 30. The longitudinal edges of each strip are turned or curled to form one-half of a flexible joint, as is clearly shown in Fig. 7. Foreign matter, such as grain or the like, is prevented from entering the flexible joints by positioning the closure 20a in the grooves 16 with the left side, as shown in Fig. 7, toward the interior of the car.

The modified form of the door post facing member 14a, shown in Fig. 4, is adapted to employ individual boards to form a closure member. In this construction the groove 16 extends from the bottom of the facing member to a point adjacent the top thereof. The groove adjacent the top of the post is expanded to the inner side of the mem-

ber, as is indicated by the reference numeral 32, and is best shown in Figs. 4 and 5.

Boards of various widths may be positioned in the expanded portion 32 of the groove 16 and then moved downwardly in the grooves 16 to form a closure member. The closure member may thus be built up to any desired height. Boards are removed from the groove 16 by raising them to the expanded portion 32 and then moving them laterally of the member 14a.

It will be apparent from the foregoing that herein is provided a device which may be economically produced and installed in any of the present type cars. Moreover, the device, when installed and in the opened position, presents no obstacle or bar to free entry into or exit from a car with which it is associated.

Furthermore, the device of this invention may be readily installed on present cars. And when so installed, the improved device provides a practically indestructible means for maintaining a closure of any desired height in a car door opening.

It will be apparent to those skilled in the art to which the device appertains, that numerous changes and alterations covering a wide range

may be made without departing from the scope or spirit of this invention. Accordingly, it is understood that the patent granted hereon is not to be limited by the specific embodiment shown or in any other way except as necessitated by the terminology of the appended claim when given the range of equivalence to which it may be entitled.

I claim as my invention:

10 In a car door construction, a door post on each side of said opening, guide and supporting means on each post for operably receiving a vertical lift closure member, said guide means including a vertical groove on each side of said door opening, the upper part of each groove being expanded to the inner edge of each door post, and a closure member operably associated with said guide and supporting members, said closure member comprising a plurality of boards in edge to edge relation, a slotted flexible member joining said boards together, each of said joined boards being independently movable a limited distance in a vertical direction in respect to said other boards and said slotted flexible joining member.

JOSEPH LUKASZEWSKI.
